INVENTOR

UNITED STATES PATENT OFFICE.

THOMAS H. REED, OF NEWARK, NEW JERSEY.

SOUND-AMPLIFIER.

1,279,438.

Specification of Letters Patent. Patented Sept. 17, 1918.

Application filed December 30, 1915. Serial No. 69,352.

To all whom it may concern:

Be it known that I, THOMAS HERBERT REED, of Newark, New Jersey, have invented certain new and useful Improvements 5 in Sound-Amplifiers, of which the following is a specification.

This invention relates to sound amplifiers, and it comprises a hollow member circular in cross section throughout a portion of its 10 length and of a different cross section throughout the remainder of its length, such construction resulting in an amplifier having one side provided with a continuous and unobstructed passage for the sound 15 waves and another side provided with a changed passage arranged to alter the volume of the sound waves and operating to modulate the sounds.

The invention further comprises an amplifier consisting of a plurality of different metals, one portion of the amplifier forming a continuous and unobstructed passage for the sound waves and the other portion forming a changed passage for decreasing 25 the volume of the sound waves, the amplifier advantageously being in communication with a tube or tone arm of different metal.

In the accompanying drawings, I have shown a specific embodiment of my invention, similar reference numerals indicating corresponding parts in the several views.

Figure 1 is an elevation of the sound amplifier;

Fig. 2 is a view looking into the outlet 35 end of the amplifier illustrating the relation of the two sections with respect to each other;

Fig. 3 is an elevation showing the manner of connecting the amplifier to the tone arm.

40 In these drawings, 1 indicates the outer section of the amplifier, advantageously made of sheet iron and being oval in cross section, but in the form of a truncated cone. The inner section 2, advantageously made of 45 polished brass is circular in cross section and is attached to section 1 by means of a joint shown at 4 in Figs. 1 and 3, solder preferably being used. The inner end of the outer section 1 preferably overlaps the 50 outer end of the inner section 2.

The outer section 1 consists of a long side 11-16 and a short side 19-15, the long side forming in connection with the adjacent section 2 a continuous straight line 55 from the outer end of the inner section 2 to

the point 16 at the outlet end of the amplifier. The short side 19-15 flares outwardly at an angle at point 19, the result is that in the upper section of the amplifier there is a straight continuous passage for the 60 sound waves while at the lower end there is a changed passage which effects a modulation of the sound.

A two-part elbow 9 and 10 soldered together is connected to the small end of section 2 and a preferably zinc tube 3 is connected to this elbow 9. The tube 3 is fitted to a socket 5 of the tone arm 6.

The long side of the amplifier from the point 16 to the elbow 9 produces a straight 70 line and combines an unobstructed passage which will be followed by the sound waves transmitted from the tone arm.

The sound waves which travel along the short side of the amplifier will be changed 75 at the point 19 by the outward flaring portion of section 1. This will cause the volume of the waves to be decreased, and as the distance between the joint 11 and the point 16 is greater than the distance between the point 15 and 19, a full modulation 80 of the tone takes place on the shorter side of the amplifier and a full volume of the tone is delivered along the long side of the amplifier.

85 The two sections 1 and 2 are of different metal and the tube 3 is preferably of a different metal from either of the sections. The joints are preferably made by overlapping the metal rather than by contacting 90 the two edges, and in this manner I eliminate all metallic rings or hollow sounds, and I also do away with any gutteral or muffled tone which is prevalent in the usual amplifier. The parts are so constructed 95 and arranged as to amplify and deliver in different degrees of volume at the same time and through the tone opening or outlet a full strength volume in one direction and a comparatively modulated volume in the 100 other direction. When the amplifier is mounted in a cabinet the elbow 9 will be located in or near the corner and the amplifier will stand diagonally across the cabinet with the outlet end flush with the front 105 of the cabinet or with the front opening of the cabinet.

110 What I claim is:

1. In a sound amplifier, the combination with a hollow member consisting of two

sections of different metals, said hollow member progressively increasing in cross sectional area.

2. In a sound amplifier, the combination with a hollow member consisting of two sections of different metals, said hollow member progressively increasing in cross sectional area, and a sound conduit of a still different metal fitted to the smaller 10 end of the hollow member.

3. In a sound amplifier, the combination with a hollow member consisting of a circular and an oval section, said sections being joined so that the wall at one side of the

largest diameter of the oval is continuous, 15 the wall of said oval section at the other end of its largest diameter joining said circular section at an angle thereby forming a changed passage, the length of the changed passage being less than that of the 20 continuous passage.

In testimony whereof, I have signed this specification in the presence of two subscribing witnesses.

THOMAS H. REED.
